United States Patent Office.

JOHN B. AIKIN, OF SOMERTON, OHIO.

Letters Patent No. 90,477, dated May 25, 1869.

IMPROVED BOOT-CRIMPER.

The Schedule referred to in these Letters Patent and making part of the same.

To all whom it may concern:

Be it known that I, JOHN B. AIKIN, of Somerton, in the county of Belmont, and State of Ohio, have invented a new and improved Boot-Crimper; and I do hereby declare that the following is a full, clear, and exact description of the construction and operation of the same, reference being had to the accompanying drawings, making a part of this specification, in which—

Figure 1 is an end elevation,

Figure 2, a side elevation, and

Figure 3, a detached view of a part of the crimping-board, or pattern, showing a portion thereof in section.

The object of this invention is to provide for public use a boot-crimper, which can be very quickly and conveniently operated, and which will crimp the boot without wrinkling the leather at the instep.

In the drawings—

A represents the frame of the machine, which resembles that of an old-fashioned hand printing-press, being supported on three legs a a^1 , and having a stout standard, a^2 , the object of which is to support the plate B, which forms the fixed jaw of the clamp.

B' is the movable jaw of the clamp, it being supported on a standard, b, which embraces and slides horizontally upon an arm or shank of the leg a^1 .

C is a screw-rod, working through a nut, c, for the purpose of moving the jaw B' back and forth, toward and from its companion B.

D is a spring-standard, supporting the rod C, and forming an abutment which confines the nut c in place, and insures the proper operation of the screw-rod, while, at the same time, it yields slightly, allowing the movable jaw to "give" as the pattern and boot are forced down between the clamps.

M is the pattern, or crimping-board, having a pin, m, at one end, and a ratchet-plate, m', at the other, as shown in fig. 1.

N is a stiff rod, constructed to fit to the inner edge of the crimping-board, and to press a smoothing-plate, O, against it at the instep of the boot, as shown in fig. 3.

The plate O is bent to conform to the angle of the instep, and is articulated to the rod N, as shown at o.

It fits like an inverted saddle over the edge of the crimping-board, extending up a short distance on each side, and operating, when pressed in place, to confine the leather firmly to the board, and prevent its slipping and wrinkling as the board and boot are forced between the clamps.

The rod N is fixed in place by fastening one end of it over the pin, or hook m, bringing the plate O into position, forcing the opposite end of the rod almost against the edge of the crimping-board, and confining

it there by means of a hook, P, articulated to the end of the rod, and engaging with the ratchet-teeth, as shown in fig. 1.

F is a vertical rack-slide, working in a suitable socket, or bed in the frame A, or standard a^2 , and capable of being moved up and down by means of a pinion, f.

G g is a gear-arrangement, for the purpose of increasing the power, and

g' is the crank by which the operator applies the power to move the slide.

f' is an arm projecting out horizontally from the slide F, and serving to support a stout bent rod, or arm, J, by means of which the pattern and boot can be forced down between the clamps.

In operation, the leather is properly cut and tacked to the board M, and is stretched or drawn up at the instep by means of the screw I and corrugated clamp, or nut I'.

The jaws B B' are then slightly separated and the board placed between them, as shown in figs. 1 and 2, and forced down a short distance by hand.

The operator then takes hold of crank g', turns it to the left, and runs the slide F and rod J up sufficiently far to allow the bent end of the rod to be brought over the apex of the pattern, and inserted into a socket, c, as shown in fig. 3.

The jaw B' is then screwed up sufficiently, and the crank g' is turned to the right, which runs the slide and bent rod J down, forcing the crimping-board and boot down between the two clamps B B', and thoroughly crimping the leather, without tearing or wrinkling it.

As the board is thus forced down, it operates like a wedge between the two clamps, its lower edge being made tapering, or wedge-form, as shown in fig. 2, to adapt it to that purpose, and it presses back the movable jaw, or clamp B', the spring D yielding to accommodate the latter, but yet holding it firmly against the crimping-board and leather.

When it is desired to raise the crimping-board, or pattern out from between the clamps, the latter are separated by means of the screw-nut c, and the crank g' is turned to the left. This raises the bent rod J, and as it rises, its notched point, engaging with a stop, t, draws up the crimping-board from between the clamps. As soon as it is clear of them, the operator, pressing his finger on the stop t, disengages it from the rod J, and removes the crimping-board.

Having thus described my invention,

What I claim as new, and desire to secure by Letters Patent, is—

1. The bent rod N, having the part O articulated to it, as shown at o, and adapted to be attached to the crimping-board by means of the pin m, rack m', and hook P, substantially as and for the purposes set forth.

2. In combination with slide F, wheels G *g*, and crank *g'*, the bent rod J, having the notch at its upper end, and adapted to operate in connection with the stop *t*, attached to the crimping-board, substantially as and for the purposes specified.

3. The combination of the spring-standard D with the nut *e*, screw-rod C, and movable jaw B', when

employed in a boot-crimper, substantially as and for the purposes set forth.

To the above specification of my invention, I have signed my hand, this 17th day of April, 1869.
